UNITED STATES PATENT OFFICE.

THEODORE G. LEWIS, OF BUFFALO, NEW YORK, ASSIGNOR TO THE BUFFALO DENTAL MANUFACTURING COMPANY, OF SAME PLACE.

DENTAL PLUGGER.

SPECIFICATION forming part of Letters Patent No. 625,043, dated May 16, 1899.

Application filed August 11, 1898. Serial No. 688,349. (No model.)

To all whom it may concern:

Be it known that I, THEODORE G. LEWIS, a citizen of the United States, residing at Buffalo, in the county of Erie and State of New York, have invented new and useful Improvements in Dental Pluggers, of which the following is a specification.

This invention relates to a dental plugger in which the tool-shank is struck by a spring-propelled hammer and in which the parts are organized to produce a long or short stroke of the hammer.

The objects of this invention are to improve the means of varying the stroke of the hammer, to improve the supports of the hammer-spring, to improve the support of the shank-spring, and to simplify and improve the catch-plate of the hammer.

In the accompanying drawings, Figure 1 is a longitudinal section of my improved dental plugger on an enlarged scale, showing the parts adjusted for producing a long stroke of the hammer. Fig. 2 is a fragmentary outside view of the upper or rear end of the plugger. Fig. 3 is a detached view of the hammer-spring and connecting parts. Fig. 4 is a fragmentary longitudinal section, on a still further enlarged scale, of the tool shank or plunger and the stop-collar mounted thereon. Fig. 5 is a cross-section thereof in line 5 5, Fig. 4. Fig. 6 is a cross-section, on an enlarged scale, in line 6 6, Fig. 1. Fig. 7 is a perspective view of the hammer. Fig. 8 is a detached perspective view of the catch-plate. Fig. 9 is a fragmentary longitudinal section of the throw-adjusting mechanism, showing the parts adjusted for producing a short throw of the hammer.

Like letters of reference refer to like parts in the several figures.

The inclosing case of the plugger consists of an upper or rear section A and a lower or front section A', which is screwed into the upper section, each section being preferably provided with a covering α of rubber.

B represents the longitudinally-movable shank or plunger, which carries the plugger-tool b at its lower or front end. This shank is arranged with its central portion in the lower case-section A', while its upper or rear end projects into the upper section of the case.

C represents the longitudinally-movable hammer, which is arranged in the upper section of the case and which is adapted to strike the upper end of the tool-shank. The lower end of the hammer, which strikes the shank, is preferably provided with a rubber plug c in order to deaden the blow.

D represents the spring whereby the tool-shank is yieldingly held in a projected position. This spring surrounds the shank within the lower case-section and bears with its upper end against a shoulder d in said section, while its lower end bears against the upper side of a collar d' on the shank. This collar is securely held against longitudinal displacement on the shank by an annular groove d^2 in the shank, in which the collar is secured, Figs. 1, 4, and 5. The collar is split on one side and sprung into this groove and soldered in place.

E represents a nipple which is screwed into the lower end of the lower case-section.

F represents an adjustable stop-sleeve, whereby the outward movement of the shank and the stroke of the hammer may be varied. This sleeve surrounds the lower portion of the tool-shank and is provided with an external screw-thread, which engages with an internal screw-thread in the nipple. The inner end of the stop-sleeve serves as an abutment against which the collar d' on the shank strikes and whereby the forward or projecting movement of the shank is arrested. This collar thus serves the double purpose of receiving the thrust of the shank-spring and limiting the forward movement of the shank.

Upon turning the adjusting-sleeve in one or the other direction it moves lengthwise in the nipple and shifts the inner abutment or stop end of the sleeve inwardly or outwardly, thereby varying the outward movement of the shank. The longitudinal movement of the adjusting-sleeve is limited by an outer stop f , Figs. 1 and 9, which is adapted to engage with the outer end of the nipple upon screwing the sleeve inwardly, and by an inner stop f' , which is adapted to engage with the inner end of the nipple upon screwing the adjusting-sleeve outwardly. The outer stop f consists, preferably, of an annular flange which is formed integrally with the adjusting-

- sleeve, and the inner stop consists of an internally-screw-threaded collar which is screwed upon the externally-screw-threaded inner end of the adjusting-sleeve. In assembling the 5 parts the inner stop f' is shifted lengthwise on the sleeve for adjusting the extent of the longitudinal movement of the sleeve and is then permanently secured to the sleeve, preferably by soldering, in order to prevent the 10 stop from becoming displaced.
- G represents the hammer-spring, arranged with its lower portion in the upper case-section and with its upper portion in an adjusting-cap H, screwed into the upper end of the 15 upper case-section. The lowermost coil h of the hammer-spring is contracted and clamped firmly around the reduced upper end or stem c' of the hammer, and the uppermost coil h' is also contracted and clamped firmly around 20 the depending stud i of a circular button I. The latter is provided with a rounded or convex back or upper side i', which is seated in a corresponding concave seat i² in the upper portion of the adjusting-cap, as shown in Fig. 25 1. The intermediate or body portion of the hammer-spring is larger in diameter than its end portions and smaller in diameter than the surrounding casing, so that the body of the spring is out of contact with the adjacent 30 parts of the plugger, thereby preventing the spring from scraping against these parts. The spring is maintained in this position by the coöperating convex and concave faces of the button and cap, which serve to center the 35 spring in the plugger. By firmly holding the spring at its ends and leaving the intermediate portion free the singing noise, which is produced by a spring having its ends uncured, is avoided. The downward movement 40 of the hammer is limited by a stop or feather j, secured to the inner side of the upper case-section below the hammer, as shown in Fig. 1. The blow of the hammer may be regulated by screwing the cap H in or out, and so varying 45 the tension of the hammer-spring, the force of the blow being readily determined by the graduations k on the outer side of the cap, as shown in Fig. 2. By interposing between the upper end of the hammer-spring and the adjusting-cap a button on which the adjusting-cap can turn the noise, which otherwise would be produced by the scraping of the end of the spring against the cap during adjustment, is avoided.
- 55 L represents the usual latch whereby the hammer is retracted and the hammer-spring is compressed and which is arranged lengthwise with its upper end in a longitudinal groove l, formed in the side of the hammer. The lower 60 end of the latch is arranged in a notch l', which is formed in a head m, secured to the upper end of the tool-shank, and is provided with a laterally-projecting toe l², which engages loosely in a transverse opening m' in the shank.
- 65 The upper end of the latch is provided on its inner side with the usual shoulder l³, which is adapted to engage either one of two shoulders

n n', which are arranged one above the other on a catch-plate N, mounted on the hammer. This plate has the form of a dovetail with the 70 shoulders arranged on the wide portion thereof and is fitted into a correspondingly-shaped groove o, which is formed transversely in the hammer and intersects the catch-groove l at right angles. The ends of the catch-plate are 75 rounded off flush with the hammer, as shown at o', Fig. 6, and bear against the inner side of the upper case-section, thereby confining the catch-plate in its groove.

By forming both catch-shoulders on one 80 plate the construction is simplified, the strength of the catch is increased, and the cost of producing the same is reduced.

By arranging the catch-shoulders on the wide side of the catch-plate the lower or front 85 edge of the plate may be utilized as the lower or front shoulder n and requires only the upper or rear shoulder n' to be cut into the catch-plate, whereas if the shoulders were arranged on the narrow side of the catch-plate both 90 shoulders would have to be cut into the same.

P represents the usual trip shoe or cam with which the upper end of the latch engages during the last portion of the upward movement of the hammer, and whereby the latch is released from the catch-plate to permit the hammer to descend or move forward and deliver the blow against the tool-shank. The trip-shoe is secured in the usual manner to the inner side of the upper case-section within the 95 latch-groove l. The latch is yieldingly pressed inwardly by a spring l⁴, so that its shoulder is in line with those of the catch-plate.

In the position of the parts represented in Fig. 1 the adjusting-sleeve is moved outwardly 105 to its fullest extent for producing a long throw or stroke of the hammer, the tool-shank is projected and bears with its collar d' against the inner end of the adjusting-sleeve, and the hammer is in its foremost position with its 110 front catch-shoulder n facing the shoulder of the latch. Upon placing the end of the tool against the tooth-filling to be plugged and then moving the case forwardly on the tool-shank the latch engages its shoulder with the 115 front or lower catch-shoulder of the hammer and stops the hammer and causes the hammer-spring to be compressed.

When it is desired to obtain a short stroke of the hammer, the adjusting-sleeve is screwed 120 inwardly until its outer stop bears against the outer end of the nipple, as shown in Fig. 9. This reduces the extent of the outward movement of the shank in the case and causes the shoulder of the latch to stand opposite the 125 upper shoulder n' of the catch-plate when the shank is in its outermost position. Upon placing the tool against a filling and moving the case forwardly when the parts are in this position the hammer is operated by the engagement of the upper catch-shoulder with that of the latch, and the latter being now nearer to the trip-cam than when it is in its 130 lowest position the latch is released sooner

from the hammer and a shorter stroke of the hammer is produced.

In the use of my improved adjusting device for changing the length of stroke of the hammer it is only necessary to screw the adjusting-sleeve inwardly or outwardly as far as possible. The extent of this movement is controlled by the outer and inner stops *f f'* on the adjusting-sleeve, and when this sleeve is shifted to either extreme of its longitudinal movement the shoulder of the latch stands normally opposite one or the other shoulder of the catch-plate and produces a short or long stroke of the hammer. The change from a short stroke to a long stroke, or vice versa, is easily and conveniently effected by the operator without requiring any particular care, as the adjusting-sleeve is stopped when it has reached the proper position. The adjusting-sleeve can be screwed sufficiently tight at either extreme of its longitudinal movement to hold it securely in position.

I claim as my invention—

1. The combination with the tool-shank provided with an annular groove and the stop-sleeve surrounding the shank, of a split collar arranged in the groove of the shank and bearing with one side against said sleeve, and a spring bearing against the opposite side of the collar, substantially as set forth.

2. The combination with the case, the tool-shank, the hammer provided with shoulders at different distances from the shank, and the latch connected with said shank and adapted to engage with either of the shoulders on the hammer, of a stop-sleeve surrounding the shank and capable of longitudinal adjustment for varying the stopping position of the shank and latch, substantially as set forth.

3. The combination with the case, the tool-shank, the hammer provided with shoulders at different distances from the shank, and the latch connected with said shank and adapted to engage with either of the shoulders on the hammer, of a stop-sleeve surrounding the tool-shank and having an external screw-thread which engages in a threaded opening in the case, whereby the sleeve may be shifted lengthwise of the shank for varying the point at which the forward movement of the shank is arrested, substantially as set forth.

4. The combination with the case, the tool-shank, the hammer provided with shoulders at different distances from the shank, and the latch connected with said shank and adapted to engage with either of the shoulders on the hammer, of a nipple attached to said case, a stop-sleeve arranged in said nipple and adapt-

ed to be engaged by a shoulder on said shank, and stops arranged on said sleeve on opposite sides of the nipple, substantially as set forth.

5. The combination with the case, the tool-shank, the hammer provided with shoulders at different distances from the shank, and the latch connected with said shank and adapted to engage with either of the shoulders on the hammer, of an internally-threaded nipple attached to said case, a screw-sleeve arranged in said nipple and adapted to be engaged by a shoulder on said shank, a stop-collar arranged on said sleeve on the outer side of the nipple, and an internally-screw-threaded stop-collar secured to the threaded portion of the sleeve on the inner side of the nipple, substantially as set forth.

6. The combination with the case, the hammer and the tool-shank, of a cap connected with the end of the case and provided with a concave seat, a button having a convex back engaging with the concave seat of the cap, and a spring connected at one end to the hammer and at its opposite end to said button, substantially as set forth.

7. The combination with the case, the hammer provided with a stem, and the tool-shank, of a cap connected with the case and provided with a concave seat, a button provided with a convex back which engages with the concave seat and having a projecting stud, and a coil-spring having its body out of contact with the case and having its end coils contracted and secured respectively to the stem of the hammer and the stud of the button, substantially as set forth.

8. The combination with the tool-shank provided with a latch, of a hammer having a longitudinal groove and a dovetail groove arranged across said latch-groove, and a dovetail catch-plate arranged in said dovetail groove across said latch-groove, substantially as set forth.

9. The combination with the tool-shank provided with a latch, of a hammer having a longitudinal latch-groove and a dovetail groove arranged across said latch-groove, and a dovetail catch-plate arranged in said dovetail groove across said latch-groove and provided in its side with shoulders, one above the other, for engagement with said latch, substantially as set forth.

Witness my hand this 9th day of August, 1898.
